(57) **CLAIM**

The ornamental design for a handle for a razor, as shown and described.

DESCRIPTION

FIG. 1 is a perspective view of a handle for a razor of the present invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines connecting the two solid contour lines along the upper front portion of the handle represent the bounds of the claim. The remaining broken lines illustrate the environment of the handle for a razor. None of the broken lines forms part of the claimed design.
